UNITED STATES PATENT OFFICE.

ETHEL L. GRIFFITH, OF GREENWOOD, INDIANA.

DESIGN FOR A SMOKER'S TRAY.

Application filed August 24, 1928. Serial No. 27,951. Term of patent 3½ years.

To all whom it may concern:

Be it known that I, ETHEL L. GRIFFITH, a citizen of the United States, residing at Greenwood, in the county of Johnson and State of Indiana, have invented a new, original, and ornamental Design for a Smoker's Tray, of which the following is a specification, reference being had to the accompanying drawing, forming part thereof.

In the drawings the figure is a perspective view of the smoker's tray.

I claim:

The ornamental design for a smoker's tray, as shown.

ETHEL L. GRIFFITH.
